US00D754226S

(12) **United States Design Patent**
Caylor et al.

(10) **Patent No.:** **US D754,226 S**
(45) **Date of Patent:** **** Apr. 19, 2016**

(54) **CHUTE**

(71) Applicant: **Silgan Containers LLC**, Woodland Hills, CA (US)

(72) Inventors: **Gunnar J. Caylor**, Antelope, CA (US); **David S. Revers**, Waukesha, WI (US); **Brandon C. Garfoot**, Stoughton, WI (US); **James B. Moses**, Galt, CA (US)

(73) Assignee: **Silgan Containers LLC**, Woodland Hills, CA (US)

(**) Term: **14 Years**

(21) Appl. No.: **29/473,496**

(22) Filed: **Nov. 22, 2013**

(51) LOC (10) Cl. **15-99**

(52) U.S. Cl.

USPC **D15/147**

(58) **Field of Classification Search**

USPC D15/28, 131, 145, 147
See application file for complete search history.

(57) **CLAIM**
We claim the ornamental design for a chute, as shown and described.

DESCRIPTION

FIG. 1 is a front perspective view of an embodiment of the claimed design;

FIG. 2 is a rear perspective view of the claimed design of FIG. 1;

FIG. 3 is a front view of the claimed design of FIG. 1;

FIG. 4 is a rear view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1;

FIG. 8 is a bottom view of the claimed design of FIG. 1;

FIG. 9 is a front perspective view of another embodiment of the claimed design;

FIG. 10 is a rear perspective view of the claimed design of FIG. 9;

FIG. 11 is a front view of the claimed design of FIG. 9;

FIG. 12 is a rear view of the claimed design of FIG. 9;

FIG. 13 is a left side view of the claimed design of FIG. 9;

FIG. 14 is a right side view of the claimed design of FIG. 9;

FIG. 15 is a top view of the claimed design of FIG. 9;

FIG. 16 is a bottom view of the claimed design of FIG. 9;

FIG. 17 is a front perspective view of another embodiment of the claimed design;

FIG. 18 is a rear perspective view of the claimed design of FIG. 17;

FIG. 19 is a front view of the claimed design of FIG. 17;

FIG. 20 is a rear view of the claimed design of FIG. 17;

FIG. 21 is a right side view of the claimed design of FIG. 17;

FIG. 22 is a left side view of the claimed design of FIG. 17;

FIG. 23 is a top view of the claimed design of FIG. 17; and,

FIG. 24 is a bottom view of the claimed design of FIG. 17.

The ornamental design which is claimed is shown in solid lines in the drawings. The broken lines in the drawings are for illustrative purposes only and form no part of the claimed design. The dot-dash lines in the drawings form a boundary of the claimed design.

1 Claim, 18 Drawing Sheets
